UNITED STATES PATENT OFFICE.

JOHN EHRHARDT, OF ST. LOUIS, MISSOURI, ASSIGNOR OF TWO-THIRDS TO
HERMAN HOPMANN, SR., AND CHARLES HOPMANN, OF SAME PLACE.

SKYLIGHT.

SPECIFICATION forming part of Letters Patent No. 292,738, dated January 29, 1884.

Application filed August 7, 1883. (No model.)

To all whom it may concern:

Be it known that I, JOHN EHRHARDT, of St. Louis, Missouri, have made a new and useful Improvement in Skylights, of which the following is a full, clear, and exact description, reference being had to the annexed drawings, making part of this specification, in which—

Figure 1 is a view in perspective of the improvement, the construction being shown in an unfinished condition; Fig. 2, a vertical cross-section of the skylight-bar, the panes and cap not being shown; and Fig. 3, a vertical cross-section, including the panes and cap.

The same letters of reference denote the same parts.

This improvement has relation to the skylight-bar, and the mode of closing the joints between the panes and the bar.

A A represent the panes.

B B represent the skylight-bar, the bar being composed of plates, which are extended vertically at b b, bent at b' b', respectively, and extended outward and upward at b², bent again, and extended horizontally farther outward at b³, bent again, and extended upward and outward to the point b⁴, at which last-named point the plates are each folded and turned back, and inward to the point b⁵. From this last-named point the plates are extended upward and inward to the point b⁶, thence directly upward to the point b⁷, thence folded and extended downward to the point b⁸, thence horizontally outward to the point b⁹, and thence upward, as shown. In this manner two gutters, C C, are formed in the bar, which receive the moisture entering between the edges a a of the panes and the plates b b. Two outer auxiliary gutters, D D, are also formed in the bar, and above

the gutters D D spaces E E are provided for the packing-strips F F, which are preferably 40 of rubber. The panes rest upon the strips F F, and at their inner edges, a a, the panes abut against or come into immediate proximity to the plates b b, respectively. The cap G is secured to the bar by means of the strips 45 g g, which in turn are fastened to the bar by means of the rivets H. These rivets H also serve to connect the plates b b. The cap extends downward, at either side of the bar, to the panes A A. The panes are sustained by 50 the packing-strips F F, which in turn and as stated are held at E E in the extensions of the plates b b. To prevent these extensions from spreading apart—that is, opening away from the plates b b—the ties I I are extended 55 from the plates b b to the extensions in the vicinity of the grooves E E.

The strips I I are suitably spaced apart to enable the moisture entering between the panes and the plates b b to pass downward 60 into the gutters C C.

I claim—

The combination of the panes A A, the plates B B, bent to form the gutters C C and D D and the grooves E E, the packing-strips 65 F F, and the cap G, the strips g g, secured to the plates B B, and the ties I I, whereby double gutters are afforded as well as a free space for the descent of the moisture between the packing and the skylight-bar plates, substantially 70 as described.

Witness my hand this 23d July, 1883.

JOHN EHRHARDT.

Witnesses:

C. D. MOODY,
HRM. HOPMANN.
